METHOD OF MANUFACTURING PENS

George E. Bartol, Jr., Wynnewood, Pa., assignor
to C. Howard Hunt Pen Company, Camden,
N. J., a corporation of New Jersey

Application May 23, 1934, Serial No. 727,077

6 Claims. (Cl. 113—32)

This invention relates to a method for manufacturing pens. The invention has particular reference to and utility in connection with pens adapted for use in fountain pen holders, although 5 the article is not limited to such use.

More specifically, the invention is concerned with the production of pens of a type having tips which are bent to increase the thickness and smoothness of the writing point. It might also 10 be mentioned that I prefer to fabricate the pens from some alloy steels such as a chromium-nickel alloy.

Some of the important and general objects of 15 the invention include increasing the durability and improving the writing characteristics of pens; making possible the production of pens having long life and good writing qualities from relatively inexpensive material such as the alloy mentioned above; and facilitating pen manufac- 20 ture.

Another object of the invention is to employ 25 bent tip portions of a pen as guides during certain steps of the fabrication, as will appear more fully hereinafter.

Other objects of the invention include the production of a pen in which the slit or slot in the 30 tip is of tapered width from the writing point upwardly between the nibs, so as effectively to feed the ink downwardly by capillary action; the arrangement of the nibs to bring the tips thereof 35 into contact with each other and preferably under some slight tension, this being of special importance where bent tabs appear at the writing tip; and the use of certain grooving toward the base of the nibs, in a particular manner more fully brought out herebelow, so as to provide 40 resilience and therefore improve the writing action.

How the foregoing objects and advantages, together with others which will occur to those 45 skilled in the art, may be obtained, will be apparent from the following discussion taken with the accompanying drawing, in which—

Figure 1 is a plan view on an enlarged scale of 50 a flat pen blank made in accordance with this invention;

Figure 2 is a partial view similar to Figure 1, illustrating an additional step of the process of manufacture;

Figures 3, 4 and 5 are further enlarged, detail and somewhat diagrammatic views showing additional process steps;

Figure 5a is a top plan view of the blank following the slotting operation shown in Figure 5;

Figure 6 is a side elevational view of a completed pen;

Figure 7 is a top plan view of the pen of Figure 6, the last two views being substantially on the scale of Figures 1 and 2; and

Figure 8 is a fragmentary sectional view taken as indicated by the section line 8—8 on Figure 7.

In the production of pens of the type here under consideration, the pen blanks are preferably stamped out of flat sheet metal ribbons, and in 10 Figure 1 a pen blank appears as having a heel part 8 and a nib part 9. At opposite sides of the tip a pair of laterally projecting tabs 10—10 appear, these tabs projecting beyond the marginal outline of the pen to be formed, as clearly seen 15 in Figures 1 and 2. While it is not essential, I prefer also to provide the pen with a pierce hole 11 toward the base of the nib.

According to this invention, subsequent to the formation of the flat blank appearing in Figure 20 1, the pen is provided with a pair of grooves 13—13 each of which is preferably extended from a point adjacent the pierce hole 11 to a point adjacent the base of the nib at the outer edge thereof as at 14, for reasons to be mentioned more 25 fully herebelow.

In the course of manufacture, according to 30 this invention, the tip part of each blank is subjected to a two-stage bending operation, the first of which appears in Figure 3 and the second in Figure 4. As seen in Figure 3, the tip part of the pen is placed over a suitable block or the like 15 having a groove in its working surface, and a tool 16 is brought down against the pen in the manner shown so as to bend the tabs 10—10 substantially along the marginal outline of the pen 35 toward one side of the flat pen blank until these tabs extend in planes approximately at right angles to each other at each side of a small central area 10a. Following this operation the pens are placed between the relatively movable elements 17 and 18 in an edgewise position so as to 40 bend the tabs or wings 10—10 into spaced but substantially parallel planes as clearly seen in Figure 4. A stop diagrammatically shown at 19 45 serves to prevent excessive bending of the tabs.

From Figure 4 it will be seen that the central area 10a still remains and that the wings 10—10 at opposite sides of this central area define a U-shaped trough as compared with the generally 50 V-shaped trough after the operation of Figure 3.

Following the foregoing bending operations, the metal of the blank between the tabs 10—10 is cut out, preferably by means of a thin abrasive wheel or equivalent "sawing" device. This opera- 55

- tion appears in Figure 5 and it is especially pointed out that the parallel and spaced tabs 10-10 are employed as guides for the abrasive wheel 20, this wheel being inserted therebetween at the commencement of the "sawing" operation. Preferably the pen tip and the disk 20 are brought together in a somewhat yielding manner so that the disk 20 may "feel" its way into the trough between the tabs 10-10. The disk employed is 10 preferably of substantially the same width as the small area 10a at the pen tip, hereinbefore mentioned, so that the metal which is cut out will permit the tabs to be brought into contact with each other in the manner described herebelow.
- 15 As seen in Figure 5a the operation of Figure 5 produces a parallel edge slot 22a which, as brought out herebelow, is subsequently closed at the tip of the pen.

Referring now to Figures 6 and 7 which are side 20 elevational and top plan views of a completed pen, after the slotting operation the pens are formed or raised to give them rounded pen point configuration. According to this invention the raising operation is carried out, as by means of 25 cooperating shaped dies, in a manner to "droop" the nib of the pen slightly, as clearly seen in Figure 6 at 21. The rounding of the pen and drooping of the nib cooperate to bring the tabs 10 into 30 contact with each other, at least adjacent the writing tip, and these operations are preferably carried out so as to place the tabs under a slight initial tension. Another important effect of the raising and drooping operations is the tapering of the slot 22 (see Fig. 7) in a manner which 35 effects a desirable capillary action in feeding ink from a region in the neighborhood of the pierce hole 11 to the tip.

It is further pointed out that the particular arrangement of grooves 13 is of advantage in connection with the drooping operation and also in 40 improving resilience of the nib even though the pen be made of fairly thick and therefore stiff sheet metal stock. A groove 13 is extended across the base part of each nib from a point adjacent 45 the upper end of the slot 22 (or adjacent to the pierce hole where this latter is provided) to a point at the outer edge of the pen at or adjacent to the junction of the nib and heel parts. The 50 importance of this will be understood to better advantage if it be remembered that the side portions of the heel 8, after the raising operation, lie in substantially upright or vertical planes, in view of which, bending of the metal adjacent the base 55 of the nib would require very heavy pressure in writing, even when the pen is formed of relatively thin sheet metal stock. By grooving the pen across the nibs at opposite sides of the central slot and extending the grooves to a point at or closely adjacent to the junction of the heel 60 part with the nib, materially improved flexibility is secured since very little if any upright or vertical metal remains in front of the grooves. While, as indicated, the outer end of each groove 13 terminates in the neighborhood of the junction 65 point between the heel and nib, it might further be mentioned that the point of termination may also be slightly above the junction point although approximately no farther than the thickness of the metal of which the pen is formed, according 70 to my preferred practice.

According to the foregoing, I am enabled to produce relatively inexpensive pens, especially for fountain pen use, which pens have materially improved writing characteristics and increased 75 strength and life, as compared with prior de-

velopments. The tabs at the tip of the pen, of course, provide a writing point of relatively great thickness or depth, so that the pen will not rapidly wear to a sharp edge or point. In addition, the grooving at the base of the nib is of advantage as above described and this particular grooving also defines or establishes lines of flexibility adjacent to the base of the nib so that the pen has improved resilience.

While securing the advantages mentioned above, the invention also provides a tapered slot 10 for ink flow, as a result of which capillary action may effectively draw the ink downwardly from a fountain pen feeder to the contacting tips formed by the bending operations.

I claim:

1. In the manufacture of pens, the method which includes forming a metallic pen blank having tabs projecting at opposite sides of the pen tip in the general plane of the blank, bending said tabs toward one side of the blank in spaced but substantially parallel relation, and utilizing said spaced tabs as guides for a cutting tool introduced therebetween and cutting out the metal between the tabs with such cutting tool.

2. In the manufacture of pens, the method which includes forming a metallic pen blank having tabs projecting at opposite sides of the pen tip, bending said tabs toward one side of the blank into relatively angled positions to form a trough therebetween having divergent side walls, subsequently additionally bending said tabs into substantially parallel, but spaced planes to form a substantially U-shaped trough for the reception of a sawing device, and utilizing said spaced tabs 30 to guide the sawing device in cutting the tip portion of the pen to form nibs.

3. In the manufacture of pens, the method which includes forming a metallic pen blank having tabs projecting at opposite sides of the pen tip, bending said tabs toward one side of the blank into relatively angled positions to form a trough therebetween having divergent side walls, subsequently additionally bending said tabs into substantially parallel, but spaced planes to form a substantially U-shaped trough for the reception of a sawing device, utilizing said spaced tabs 40 to guide the sawing device in cutting the tip portion of the pen to form nibs, and bending said nibs to bring the tabs into contact with each 45 other adjacent the writing tip.

4. In the manufacture of pens, the steps of forming a pen blank having tabs projecting laterally from opposite sides of the tip beyond the marginal outline of pen to be formed, bending 50 said tabs in a direction transverse of the plane of the blank on lines substantially coinciding with said marginal outline, the bent tabs being spaced from each other, thereafter cutting out and removing a strip of metal extending along the 55 major axis of the pen and between said bent tabs, the width of said strip being substantially equal to the space between said tabs to form a pair of nib parts with a slot therebetween, and bending the nib parts to bring said tabs together and substantially close said slot at the writing tip of the pen, but leave said slot open toward its inner 60 end.

5. In the manufacture of pens, the steps of forming a pen blank having tabs projecting laterally from opposite sides of the tip beyond the marginal outline of pen to be formed, bending 70 said tabs in a direction transverse of the plane of the blank on lines substantially coinciding with said marginal outline, the bending being

sufficient to form a trough having divergent side walls, subsequently additionally bending the tabs to bring them into substantially parallel but spaced relation, thereafter cutting out and removing a strip of metal extending along the major axis of the pen and between said bent tabs the width of said strip being substantially equal to the space between said tabs to form a pair of nib parts with a slot therebetween, and bending the nib parts to bring said tabs together and substantially close said slot at the writing tip of the pen, but leave said slot open toward its inner end.

6. In the manufacture of pens, the steps of forming a pen blank having tabs projecting laterally from opposite sides of the tip beyond the

marginal outline of pen to be formed, bending said tabs in a direction transverse of the plane of the blank on lines substantially coinciding with said marginal outline, the bending being sufficient to bring the tabs into substantially parallel but spaced relation, thereafter cutting out and removing a strip of metal extending along the major axis of the pen and between said bent tabs, the width of said strip being substantially equal to the space between said tabs to form a pair of nib parts with a slot therebetween, and bending the nib parts to bring said tabs together and substantially close said slot at the writing tip of the pen, but leaves said slot open toward its inner end.
